UNITED STATES PATENT OFFICE

LEON J. BARRETT, OF WORCESTER, MASSACHUSETTS

CENTRIFUGAL

Application filed February 21, 1927. Serial No. 169,832.

This invention relates to a centrifugal machine for separating liquids from solids or a heavy liquid from a lighter one.

The principal objects of the invention are to provide a support for the vertical shaft of the machine located in such position as to centralize the shaft at the extreme bottom for the purpose of diminishing or eliminating vibration; to provide means for taking the side thrust near the supporting means; to provide flexible means to hold the rotating unit in upright position when it is being loaded or unloaded; to provide means by which steam or a cleaning solution can be piped into the machine while the machine is running for the purpose of cleaning the solid materials which have been acted upon; and to provide practical connections by which these results can be accomplished.

Other objects and advantages of the invention will appear hereinafter.

Reference is to be had to the accompanying drawings in which

Fig. 1 is a central vertical sectional view, with parts in side elevation, showing a preferred embodiment of this invention complete and driven by gearing;

Fig. 2 is a similar view showing a corresponding machine with the lower part in elevation and motor driven and without the steam arrangement;

Fig. 3 is a central sectional view of the bearings and motor connection for the same; and

Fig. 4 is a sectional view on the line 4—4 of Fig. 3.

Referring first to Fig. 1, it will be seen that I have shown a centrifugal machine comprising a casing 10 and a perforated revolvable container 11 therein fixed to a vertical shaft 12. The container has a cover 9 which rotates with it. The casing or tank 10 has a circular top 8 on which fits a cover 46. The shaft 12 is sustained by roller bearings 13 and is driven from a power shaft 14. This shaft drives a vertical shaft 15 by bevel gears 16 which in turn by gear 18 drives an external gear 17 on a rotatable spider 19. This spider is sustained by roller bearings 21 on a central hub 20, fixed on the base 22 of the machine.

The spider 19 carries at the top and in central alignment with the hub 20 and the shaft 12, a ball 23 which fits in a hemi-spherical recess in the bottom of a head 24 which is fixed to the bottom of the shaft 12 to rotate with it. This constitutes a pivot seat for the shaft located at, or beyond, its lower end. The spider 19 carries four studs 25 evenly spaced around the pivot seat, each one having a spherical head or roll 26 at the top entering a drilled hole 27 in the bottom of a head 24. These take the side thrust.

The inner race of the roller bearing 13 is mounted on a sleeve provided with a space in which is a coil spring 28 around the shaft, bearing in a groove 29 at the top of the hub 24. These parts of course rotate together. The outer race of the roller bearing is mounted in the top of a housing 31 which extends down around the parts below and is spaced 70 therefrom. This has a series of drilled holes 32 extending up from the bottom for receiving studs 33 mounted on the base and having spherical heads like the studs 25 for taking the side thrust.

The housing 31 has a horizontal flange 34 at the bottom which is provided with openings, preferably four around the center, each one provided with a flexibly supported rod 35 extending through it and extending up 80 through a hole in a projecting part 37 on the base. These parts are yieldingly separated by springs 38 which rest on the stationary base and constitute in effect flexible legs tending to hold the rotating unit in upright position. The flexibility of these legs is helpful owing to the unbalanced loads which occur in the loading and unloading of the container 11 and the nature of the material therein.

It will be seen that the bearing 23 is at or beyond the end of the shaft. This centralizes the lower end of the shaft and prevents vibration at that point. When the machine starts to accelerate, it wobbles and the spring legs 35 assist in steadyng it by compression as the wobbling takes place in the early stages. Either function is merely to steady the rotating unit in an upright position when it is being loaded and started to rotate.

This machine requires no shock-absorbers as there is no shock to absorb. There is no mechanical compensation for the running out of true of the shaft. It runs as smoothly as an unbalanced vertical shaft can be made to run by overcoming the force of gravity by a greater centrifugal force. The wobbling which in other machines causes vibration, is an easy mechanical motion on the central bearing. As the speed is increased, the wobbling diminishes until at about 1200 R. P. M. it runs in balance. Before that time, when not running perfectly true to an unbalanced load, it cannot vibrate to the point of shaking the machine. This is due to the fact that the action is gyroscopic and does not have enough opposition to cause vibration.

Another feature is shown at the top of the machine in Fig. 1. The shaft 12 is screw-threaded at its top with a coarse thread and provided with a steam inlet 40 down through the center which communicates with grooves 41 in the interior of a sleeve 42 on the shaft 12. These grooves have outlets 43 near the bottom of the container 11. Steam is admitted to these parts through steam pipe 44 and a flexible hose 45 or another fluid cleansing medium through pipe 44^a. This flexible hose passes through an opening in the bottom flange of the cover 46 and into a non-rotatable steam head 47 on top of the shaft which has a space therein communicating with the passage 40. This is to permit the steam to be forced through the articles in the centrifugal container 11 for cleaning the same when desired. These parts are made steam tight by a packing 48 between the head 47 and a stuffing box 49 rotating with the shaft 12 and carrying the ball bearing. On the box 49 is fixed a wrench 60 for use in taking it off the shaft. A lock nut having a projecting handle 61 is also shown.

The steam is used for this purpose after the centrifugal has operated to separate the liquid as much as possible. The centrifugal force draws it into the swirl and causes it to permeate the contents of the container. It passes to the rim where it is expelled to the outer drum or casing 10 which confines its direction to the base reservoir or orifice of discharge. Thus a washing and drying machine is obtained for small metal articles which are covered with oil or other soluble substance and require cleaning for plating, packing and the like.

In Fig. 2, I have shown the invention in a simpler form in which the parts not otherwise referred to are made the same as above described. Here the central shaft 12 is operated by a motor 50 directly mounted thereon. Here the socket bearing is attached to the motor housing 56 and does not revolve. It centralizes the lower end of the shaft as in the other case and the four studs 25 are used

as before and likewise the flexible legs 35. The construction of these legs may be the same as in the other case. Of course it will be seen here that the central spherical bearing 23 is mounted on the base 52 in this case directly and not through another element. The bottom of the shaft 12 is supported in a roller bearing 53 which is mounted in a hub at the bottom of the housing 56. A plate 54 supports the centrifugal through the bearing 23.

This is an electrical direct driven construction having the same advantages as the gear driven arrangement shown in Fig. 1. The steam connections are not shown in these figures for the sake of simplicity.

Although I have illustrated and described only two forms of the invention I am aware of the fact that other modifications can be made therein by any person skilled in the art without departing from the scope of the invention as expressed in the claims.

Therefore, I do not wish to be limited to all the details of construction herein shown and described, but what I do claim is:—

1. In a centrifugal machine, the combination with a vertical shaft and a perforated container fixed thereto near the top thereof, bearings for the shaft separated widely apart, one of them being located at the bottom and the other at a point just below the container, a pivotal support for the shaft located at the bottom of the shaft and in fixed position, a member at the bottom of the shaft fixed with respect thereto having a hemi-spherical bearing for said pivotal support and provided with openings therein extending upwardly from the bottom, and a plurality of studs located in fixed position and projecting up into said openings for receiving the side thrust and limiting the lateral motion of the shaft about said support.

2. In a centrifugal extractor, the combination with a vertical shaft and a perforated container mounted at the top thereof, of a housing surrounding the shaft at the bottom and extending downwardly, a universal bearing for the shaft below the bottom thereof within the housing, means connected with the housing for holding the shaft in vertical position under unbalanced loads, a support below the bottom of the shaft having means extending upwardly for taking the side thrust from the shaft, means on a stationary part of the base of the machine for taking the side thrust of the housing, a gear on said support, and geared means for driving said gear to rotate the shaft.

3. In a centrifugal machine, the combination with a vertical shaft supported at the bottom only, a universal bearing at the bottom for supporting the shaft and a container mounted on the upper end of the shaft, of means for driving the shaft at a high rate of speed connected with the shaft at a point

near the lower end thereof, means for introducing steam into the top of said shaft from above, and a sleeve fixed to the container for receiving said shaft, said sleeve having passages for conducting the steam downwardly and outwardly in a radial direction into the bottom of a container.

4. In a centrifugal machine, the combination with a vertical shaft and a container mounted near the top thereof, said shaft having a passage down through it from the top, and means in the shaft for conducting a fluid through the passage and into the bottom of the container, of a head at the top of the shaft, means for introducing fluid into the head and down through the shaft, and a packing between the stationary steam head and the rotary shaft.

5. In a centrifugal machine, the combination with a vertical shaft and a container mounted near the top thereof, said shaft having a passage down through it from the top, of a head at the top of the shaft, means for introducing fluid into the head and down through the shaft, a box mounted to rotate with the shaft, and a packing between the rotary box and stationary steam head.

6. In a centrifugal machine, the combination with a vertical shaft and a perforated container mounted near the top thereof, said shaft having a passage down through it from the top, and means for conducting a fluid through the passage and into the bottom of the container, of a steam head at the top of the shaft, means for introducing steam into the head and down through the shaft, a box surrounding the top of the shaft and rotatable therewith, said box and head supporting the two parts of a ball bearing, a wrench carried by the box, and a lock nut also carried by the box and having a handle for loosening it.

7. In a centrifugal machine, the combination with a vertical shaft and a container mounted at the top thereof, with a housing having bearings for the shaft located below the container and laterally movable therewith but not rotatable, a universal bearing for the shaft below the bottom thereof, a stationary base, and a spider rotatable on the base and supporting said universal bearing.

8. In a centrifugal machine, the combination with a vertical shaft supported at the bottom only, a universal bearing at the bottom for supporting the shaft and a container mounted on the upper end of the shaft, of a motor, a spider to which the motor is geared for driving the shaft connected with the shaft at a series of points near the lower end thereof, and a bearing for the spider below the bottom of the shaft.

In testimony whereof I have hereunto affixed my signature.

LEON J. BARRETT.
